UNITED STATES PATENT OFFICE.

JOHN S. BOHN AND HUBERT J. WAGER, OF TITUSVILLE, PENNSYLVANIA.

DESIGN FOR A PLATFORM FOR BUCKBOARDS.

SPECIFICATION forming part of Design No. 35,150, dated October 1, 1901.

Application filed August 26, 1901. Serial No. 73,404. Term of patent 7 years.

To all whom it may concern:

Be it known that we, JOHN S. BOHN and HUBERT J. WAGER, citizens of the United States, residing at Titusville, in the county of Crawford, State of Pennsylvania, have invented and produced a certain new and original Design for a Platform for Buckboards, of which the following is a specification, reference being had therein to the accompanying drawings.

Figure 1 is a plan of the platform for buckboards, showing the new design; and Fig. 2 is a side elevation thereof.

As shown in the drawings, the leading or material feature of the design consists of the opposite parallel side rails A, having diagonally-disposed portions A', disposed toward each other, the parallel straight portions A² and the upwardly-inclined portions A³ being connected at their ends by a cross-bar A⁴. Disposed between the parallel side bars A are a series of longitudinal slats B, having parallel edges, those nearest each of the bars being provided with a beveled end B', extend-

ing parallel to the portion A' of the side bars, 25 while the central slats B are extended beyond the edge slats, as shown at B², and parallel with the portions A² of the side bars. The side bars and slats are connected together at one end by means of cross-bars C, 30 extending beneath the same, and at the opposite end by means of a cross-bar C', while intermediate of these bars a further cross-bar C² is adapted to connect the bars and slats together and also support the ends B', before 35 described.

Having described the invention, what is claimed is—

The design for a platform for buckboards, as herein shown and described. 40

In testimony whereof we affix our signatures in presence of two witnesses.

JOHN S. BOHN.
HUBERT J. WAGER.

Witnesses:

F. S. FLUROY,
J. W. THOMPSON.
